UNITED STATES PATENT OFFICE.

NESTOR L. JONES, OF MARINER HARBOR, NEW YORK.

DESIGN FOR A HAMMER-HEAD.

SPECIFICATION forming part of Design No. 34,657, dated June 11, 1901.

Application filed May 14, 1901. Serial No. 60,245. Term of patent 14 years.

To all whom it may concern:

Be it known that I, NESTOR L. JONES, a citizen of the United States, residing at Mariner Harbor, in the county of Richmond and State of New York, have invented and produced a new and original Design for Hammer-Heads, of which the following is a full and complete specification, such as will enable those skilled in the art to which it appertains to make and use the same.

In the accompanying drawings, Figure 1 is a side elevation of a hammer-head embodying my design. Fig. 2 is an inverted plan view of the same. Fig. 3 is a plan view thereof. Fig. 4 is a central vertical section therethrough, and Fig. 5 is a transverse section on the line X X of Fig. 3.

As shown in the drawings, my design in its leading and material features consists of a main body A, formed at one end with an annular extension B and upon its under face with central downwardly-projecting portion C, through which and through the head extends a sectional elliptical opening D, and formed upon its upper face with an upwardly-projecting portion A', which is segmentally curved at A² and tapers downwardly almost

to a point at A³, being cut out in a V-shaped form at A⁴, its V-shaped groove being downwardly dovetailed, as shown at A⁵ in Fig. 5, 30 and being curved upwardly at A⁶, as shown in Fig. 4, the base-line of the groove continuing outwardly from A⁷ and curving around downwardly, the head being formed beneath the same with a spherical extension E, which 35 at the sides of the hammer-head meets the main body A in the form of inwardly-curved vertical grooves F, ranging on a line approximately coincident with the side lines of the curved portion A², near where it approaches 40 the end A⁸.

Having fully described my invention, what I claim as new, and desire to secure by Letters Patent, is—

The design for a hammer-head, herein 45 shown and described.

In testimony that I claim the foregoing as my invention I have signed my name, in presence of the subscribing witnesses, this 9th day of May, 1901.

NESTOR L. JONES.
